UNITED STATES PATENT OFFICE.

CHARLES E. MATTISON, OF LAKE CHARLES, LOUISIANA.

SCREEN FOR DOORS AND WINDOWS.

1,095,340.

Specification of Letters Patent.

Patented May 5, 1914.

Application filed October 31, 1912. Serial No. 728,947.

To all whom it may concern:

Be it known that I, CHARLES E. MATTISON, a citizen of the United States, residing at Lake Charles, in the parish of Calcasieu and

5 State of Louisiana, have invented a new and useful Screen for Doors and Windows, of which the following is a specification.

This invention relates to screens for doors and windows, its principal object being to 10 provide an all metal device of this character which can be used in the same manner as an ordinary window or door screen and which is provided with means whereby the entrance of unauthorized persons through 15 doors or windows is prevented.

Another object is to provide a screen of this character which is comparatively simple in construction and which is attractive in appearance.

20 With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.

30 In the accompanying drawings the preferred forms of the invention have been shown.

In said drawings:—Figure 1 is an elevation of a portion of a screen door embodying the present improvements. Fig. 2 is a section on line A—B Fig. 1. Fig. 3 is a view partly in section and partly in elevation showing one of the cross bars and the adjacent parts of the sides of the screen 40 frame. Fig. 4 is a view similar to Fig. 1 but showing a slightly modified form of structure. Fig. 5 is a section on line C—D Fig. 4.

45 Referring to the figures by characters of reference 1 designates the sides of a screen, the same being made of pipe sections connected by T-joints 2. The top and bottom rails 3 of the screen frame are formed of lengths of pipe and the ends of these top and bottom rails are connected to the side rails by means of elbows 4, these elbows being angular as shown in Fig. 1. Each elbow has a flat outer face but a round threaded interior. It will be noted that the ends of 50 the sides 1 and of the top and bottom rails 3 are reduced in diameter to form screw

threaded nipples so that, when the nipples are in engagement with the elbows 4, the outermost surfaces of the rails are disposed flush with the corresponding surfaces of the elbows and it is thus possible for the frame to rest flat upon a supporting structure and to fit snugly against the sides of a door or window frame. The T-joints 2 are engaged by the threaded ends of cross bars 5, each bar being preferably tubular and having its ends provided with right and left hand threads respectively. These bars are preferably spaced about six inches apart so as thus to constitute guards to prevent persons from passing through the screen frame after cutting the wire fabric therefrom. This wire fabric has been indicated at 6 and its edge portions are attached to the frame of the screen by means of metal 70 clamping strips 7 which are attached to the sides, top and bottom of the frame by means of screws 8 or the like. It is preferred to have each side and the top and bottom of the frame provided with a flat face such as 80 shown at 9 in Fig. 2 and on which the edge portions of the screen fabric rest. It will be apparent that with this construction the screen fabric 6 can be removed whenever desired and a new one substituted therefor. 85 The frame of the screen is practically indestructible and, when once secured in position, will act as an efficient guard to prevent persons from entering the building through the doors or windows in which the screens 90 are secured.

Instead of forming the top and bottom rails of the screen of tubes, as shown in Fig. 1, bars 10 may be interposed between the ends of the sides 11 of the screen frame as 95 shown in Fig. 4, the ends of the bars being concaved, as shown at 12 in Fig. 5, so as to straddle the sides of the screen frame. Furthermore, if desired, dowels 13 or the like may be arranged in the concaved ends 12 so 100 as to engage the sides 11. By utilizing bars such as described, the ends of the sides can be cut off square and there will thus be no difficulty in providing a frame which will be perfectly rectangular. The cross bars 14 105 which correspond to the bars 5, will of course hold the sides 11 properly assembled with relation to the top and bottom rails 10.

Instead of forming the side rails of sections of pipe and of T-couplings, each side 110 can be formed in a single piece of the contour shown in Fig. 5.

What is claimed is:—

A screen including a frame made up of detachably connected tubular side members, top and bottom rails connected to the ends thereof, each of said members and rails having a flat fabric engaging surface, a screen fabric mounted at its edges on said flat surfaces, means for clamping the fabric upon said surfaces, there being inwardly extending tubular portions upon certain of the tubular side members, said portions being lapped by the screen fabric, and cross bars

having threaded ends screwed into the said inwardly extending tubular portions and connecting the sides of the frame and constituting a grating. 15

In testimony that I claim the foregoing as my own, I have hereto affixed my signature in the presence of two witnesses.

CHARLEY E. MATTISON.
